PROFILE GAUGE

Ernest C. Whitney, Danvers, Mass., assignor to
 Stockton Profile Gage Corporation, Lowell,
 Mass., a corporation of Massachusetts

Application March 28, 1934, Serial No. 717,786

9 Claims. (Cl. 33—175)

This invention relates to conforming or profile gauges. It has for its general object to facilitate the manufacture of devices of this kind, to adapt such gauges to a wider range of work, and to devise a construction in which those changes necessary to adapt a gauge to the requirements of different kinds of work can be easily and quickly made either by the user or by the manufacturer.

10 The nature of the invention will be readily understood from the following description when read in connection with the accompanying drawing, and the novel features will be particularly pointed out in the appended claims.

15 In the drawing,

Figure 1 is a plan view of a gauge constructed in accordance with this invention;

Fig. 2 is an end view of the device shown in Fig. 1;

20 Fig. 3 is a perspective view of certain elements of said gauge illustrating details of manufacture;

Fig. 4 is a top edge view of the gauge illustrated in Fig. 1; and

25 Fig. 5 is a view similar to Fig. 1 illustrating a modification.

A typical profile gauge comprises a series of laminations, with some kind of a supporting means for them to hold them side by side in parallel relationship and for individual adjustment relatively to each other while maintaining them in their parallel relationship. For most purposes these gauges can be made in certain more or less standard sizes so far as the dimensions of 30 the laminations are concerned, much of the variation consisting in the character of the base to which the assembly of laminations is secured. One feature of this invention deals with this condition and involves a construction which permits 35 the use of different forms or bases interchangeably with a single series of laminations.

Such a construction is illustrated in Figs. 1 to 4, inclusive. It comprises a series of laminations 2, each relatively long and narrow and each provided with a longitudinal slot, as shown at 3 in Figs. 2 and 3. For the purpose of supporting these laminations in their operative relationship to each other, they are all threaded on a bar 4, of rectangular form in cross-section, and of such 40 a width and thickness that it permits the laminations to slide freely on it but holds them against any substantial swinging movement with reference to each other. In other words, it maintains them in their parallel relationship at all times 45 and notwithstanding their individual adjusta-

bility. At one end the bar 4 is provided with an end piece or head 5 which prevents the laminations from slipping off this end of the bar, and at its other end it has a reduced screw threaded stem 6 on which is mounted a clamping shoe 7 and a knurled clamping nut 8.

As above indicated, this assembly may be used in a great variety of kinds of work when operatively associated with a suitable form of base, the nature of the base, however, varying with the use to which the device is to be put. In order to provide for the attachment of bases interchangeably to the assembly described, the head or end piece 5 is made of a dove-tail form, as best shown in Figs. 3 and 4, and the base 10 has a recess or slot 12 formed in it, complementary in shape to the part 5, so as to receive this member with the latter tightly fitting in the recess or socket, and thus securing the base and the bar 4 rigidly together. Various arrangements may be provided for releasably securing the parts in this relationship. In the particular construction shown in Figs. 3 and 4, the end piece 5 is provided with a spring latch 14 having a projecting but retractable end a adapted to enter a hole 15, 20 Fig. 3, in the wall of the socket 12 when the end piece is firmly seated therein, and thus to lock the end piece securely in its socket. At the same time the latch can readily be withdrawn whenever desired, thus releasing the base 10 from the 30 laminations and their supporting means, and permitting this whole assembly to be removed as a unit and secured to another base of a different form.

As above stated, other arrangements may be provided for releasably securing the end piece 5 in its socket, and one such construction is illustrated in Fig. 5 in which this securing function is performed by a machine screw 16.

Such arrangements as those above described facilitate the manufacture of different styles of profile gauges, and the changing of bases as required by the user to adapt an individual gauge to different kinds of work.

An important use for profile gauges is found in the inspection of the contours of the tread faces of locomotive and car wheels to determine the extent to which wear has progressed and whether or not it has reached such a point as to necessitate the repair or scrapping of the wheel. Ordinarily three main contours are made use of on an individual road: one for the wheels of passenger locomotives, another for those of freight locomotives, and a third for car wheels. The drawing shows at 17 a typical form of templet for 50 55

this purpose, the templet being set into the side of the base 10 and removably secured thereto by screws 18 so that this templet can be removed, whenever desired, and replaced by another of a different form. The templet is located closely beside and extends parallel to the assembly of laminations 2. Consequently, when this gauge is placed upon the tread or rim of a locomotive wheel and the laminations are made to conform 5 to its contour, a comparison of its profile with that of the templet may quickly be made and the degree of wear can readily be determined. In using the gauge in this manner the base 10 is placed against the vertical face of the wheel adjacent to the flange, the nut 8 is loosened, and the lower edges of the laminations 2 are pressed down radially of the wheel against its rim, until the lower edge of the templet 17 is brought close 10 to the surface of the rim.

20 In this connection it is especially desirable to determine the extent to which the thickness of the flange has been diminished, and in order to refer a definite point on the flange to a corresponding point on the templet, a special lamination b is included in the series at a definite distance from 25 the base 10. Since the inner face of the base rests against the inner face of the wheel, and the minimum thickness of flange permissible, at least on many roads, is fifteen-sixteenths of an inch, this special lamination b is located at said distance from the inner face of the base 10. It thus is very 30 easy to determine whether or not wear has progressed to such a point that the limit of minimum thickness has been reached.

35 Another important point in the contour of a wheel rim is the middle of the tread which, in a typical wheel, is two and seven-eighths inches from its inner face. Accordingly, in the gauge shown in Fig. 1 another special lamination c is 40 inserted at this point. These special laminations may conveniently be made of some different material from that of which the others are composed, so that they will easily be recognizable. Usually it is preferable to make the laminations 45 2 of aluminum, or some aluminum alloy, in which case the special laminations b and c may be made of brass or bronze so that they will present an appearance contrasting sharply with that of the others.

50 If desired, the upper edge of the templet bar or plate 17 may be graduated in inches or fractions thereof, or in other linear dimensions. Also, the nut 8 may be replaced by a special nut 8', Fig. 4, having a handle to facilitate the location or manipulation of the gauge. Usually car and locomotive wheels are inspected at approximately 55 regular intervals, and in order to start successive gauging operations from the same point on an individual wheel during different inspections, a hole 20 is drilled through the base 10 to receive a prick punch, thus enabling the inspector to 60 make a punch mark on each wheel during the first inspection and to use this mark in making later inspections as the point from which to start the 65 gauging operation.

65 While a gauge of this character is particularly useful for the purposes above described, similar constructions in which different templets are used may be employed to advantage in a considerable variety of other relationships.

70 The gauge shown in Fig. 5 is like that illustrated in Fig. 1 except that the templet bar or plate 17 has been replaced by a bar 21, graduated in inches, and having its upper edge extending 75 at right angles to the base 10 so that it can be

used as a square, this upper edge being either registered with or offset by a predetermined distance from the upper edges of the laminations when they are at the limit of their downward movement. Masons, mechanics, and other artisans, find this type of gauge highly useful in their work. It is of advantage also to include special laminations d at definitely spaced intervals as, for example, one inch apart, in a gauge of this type. In addition, a group of laminations, such as those shown at e, may be graduated in inches and fractions thereof, or according to the metric system, these graduations running transversely to those on the bar 21 and cooperating with said bar to indicate the degree of vertical displacement of the laminations. This arrangement also is useful in the construction shown in Fig. 1. Where additional lines parallel to the bar 21 are desired for convenience in determining the degree to which individual laminations are displaced, a groove or line 22, Fig. 5, may be made across the entire series of laminations and running on to the shank of the bar 21 where it overlies the base 10, so that this line will be straight when all of the laminations are in their initial or zero positions, and the displacement of individual laminations may be determined by reference to it.

Having thus described my invention, what I desire to claim as new is:

1. In a profile gauge, the combination with an assembly comprising a series of laminations and means operatively supporting said laminations side by side in parallel relationship to each other for independent sliding movement while maintaining them in said parallel relationship, of a templet, and means for removably securing said assembly and said templet together in cooperative relationship to each other, whereby said templet may be removed and another of a different form substituted for it, said means supporting said templet closely beside and approximately parallel with said laminations.

2. In a profile gauge, the combination with an assembly comprising a series of laminations and means operatively supporting said laminations side by side in parallel relationship to each other for independent sliding movement while maintaining them in said parallel relationship, of a base to which said assembly is operatively secured, and a templet removably fastened to said base, the templet and said laminations being located closely beside and parallel with each other.

3. In a profile gauge, the combination with an assembly comprising a series of laminations and means operatively supporting said laminations side by side in parallel relationship to each other for independent sliding movement while maintaining them in said parallel relationship, of a base to which said assembly is operatively secured, a templet set into the side of said base, and means for removably securing said templet to the base, the templet and said laminations being located closely beside and parallel with each other.

4. In a profile gauge, the combination with an assembly comprising a series of laminations and means operatively supporting said laminations side by side in parallel relationship to each other for independent sliding movement while maintaining them in said parallel relationship, said assembly including an end piece, and means for clamping said laminations against said end piece, of a base to which said end piece is rigidly but

removably secured, whereby different bases may be interchangeably secured to said assembly.

5. In a profile gauge, the combination with an assembly comprising a series of laminations and means operatively supporting said laminations side by side in parallel relationship to each other for independent sliding movement while maintaining them in said parallel relationship, said supporting means including an end piece projecting beyond one end of the series of laminations, means for clamping said laminations against said end piece, of a base recessed to receive said end piece, and means for securing said end piece rigidly but removably in said base, whereby said assembly may be removed as a unit from said base and secured to another base having different characteristics.

6. In a profile gauge according to preceding claim 5, a construction in which said securing means includes a releasable latch.

7. In a profile gauge, the combination of an assembly comprising a series of laminations and means operatively supporting said laminations side by side in parallel relationship to each other for independent sliding movement while maintaining them in said parallel relationship, and a templet secured to said supporting means and located closely beside said series of laminations and parallel with them, one of said laminations

presenting an appearance contrasting with that of the others and being located in a predetermined relationship to the contour of said templet, whereby it cooperates with the other elements of the gauge to designate the positional relationship between a definite portion of the work and a part of the templet.

8. In a profile gauge, the combination of an assembly comprising a series of laminations and means operatively supporting said laminations side by side in parallel relationship to each other for independent sliding movement while maintaining them in said parallel relationship, one of said laminations being located between the others and at a predetermined distance from one end of said series and presenting an appearance contrasting with that of the adjacent laminations.

9. In a profile gauge, the combination of an assembly comprising a series of laminations and means operatively supporting said laminations side by side in parallel relationship to each other for independent sliding movement while maintaining them in said parallel relationship, a series of laminations interspersed with the others at predetermined distances apart and of contrasting appearance, whereby they serve to designate predetermined spacings.

ERNEST C. WHITNEY.
